ELECTRIC TOOTHBRUSH KIT

Frederick W. Perl, Mansfield, Ohio, assignor to Westinghouse Electric Corporation, East Pittsburgh, Pa., a corporation of Pennsylvania

Filed Aug. 24, 1964, Ser. No. 31,424

Term of patent 14 years

(Cl. D4—3)

FIG. 1.

FIG. 2.

FIG. 4.

FIG. 3.

FIGURE 1 is a top plan view of an electric toothbrush kit embodying my invention;

FIG. 2 is a side elevational view thereof;

FIG. 3 is a front elevational view thereof; and

FIG. 4 is a rear elevational view thereof.

The side not shown in FIG. 2 is similar in appearance to the side therein shown.

The dominant features of my design reside in the parts shown in the full lines.

I claim:

The ornamental design for an electric toothbrush kit, as shown and described.
